United States Patent Office.

GEORGE B. KIRKHAM, OF NEW YORK, N. Y.

Letters Patent No. 64,986, dated May 21, 1867.

IMPROVEMENT IN ORGANS.

The Schedule referred to in these Letters Patent and making part of the same.

TO ALL WHOM IT MAY CONCERN:

Be it known that I, GEORGE BYRON KIRKHAM, of 167 East Thirty-Third street, city, county, and State of New York, have invented a new and useful improvement in Organs, Pianos, &c., which I term a "Grand Accord;" and I do hereby declare the following to be a full, clear, and exact description of the same, sufficient to enable one skilled in the art to which the invention appertains to make use of it, reference being had to the accompanying drawings, which form a part of this specification, and in which—

Figure 1 represents a general perspective view of the improvement as applied to pianos, omitting some of the details, (which are introduced in the other figures,) to prevent confusion.

Figure 2 shows an enlarged view of *a*, with its attendant fixtures and appliances.

Figure 3 represents a side view of *a*, with its accessories.

Figure 4 is an under view of *a*.

This improvement, which I term a "Grand Accord," for organs, pianos, melodeons, &c., is designed to raise or lower the pitch of the instrument a half-tone, full tone, or more, above or below its usual or normal condition, at the pleasure of the performer, thus enabling him to transpose or chord with another instrument. The first great peculiarity of this invention is having the key-sticks *x* and hammer-sticks *y*, or those that act on the wires, reeds, pipes, &c., severed from each other at *z*, and hinging them by the plate *z* and little pins passing through the sticks, as shown in the design. The sticks thus severed act on each other by means of connections *a a*, which connections *a* are held up and moved right and left by the bar *b*, being fastened to the bar *b* by little nuts and screws, with a globe or ball-rest at the lower end *c e*, shown plainly in fig. 4. These connections *a a* are pivoted or secured to the keys by little conical nuts and screws *d d*, passing through the blocks *e* into the key-sticks. At the other ends of *a a* are lips or catches *f f*, rigidly secured to the hammer-sticks *y*, which catches *f f* are lined on the inside with leather or other soft substance to make them grasp the connections *a a* firmly. The lips *f f* have each a small wire and screws to hold it, *g g*, to steady the lips and keep them from interfering with each other. Furthermore, as the connections *a a* would in time, if not at first, be sure to work loosely in the lips *f f*, thus making a disagreeable rattling, a spring-catch, *h*, is added to the connection *a*, in such a manner as to bring it in close contact with the upper part of the lip *f*. This catch *h* plays up and down on the pin *j*, being pressed up by the springs *k* and *l*, while it is held to the lips *f* by the pin *i*, which pin *i* is raised or lowered by the elbow *m*, and, by means of the appliances *n*, *o*, *p*, and *q*, is placed within the control of the performer, enabling him to loosen or tighten the pressure, especially when shifting the connections. In short, the bar *b*, the connections *a a*, with their catches *h h*, &c., can all be moved to the right or left from their first lips *f f* to others, and thus cause the keys to operate on different wires, reeds, or pipes, higher or lower, as the case may be, from those that they first engaged. The moving apparatus is a rod, *r*, with an adjusting-nut at *s*, which rod *r* is secured to the pedestal *t*, rigidly fastened to the segment *u*, and, by means of the dial *w*, which has marked on it a half-tone, one tone, tone and a-half, and so on, the instrumentalist can guide the index-pointer to the higher or lower tone required, thus, by means of the cog-wheel *v*, moving *u*, *r*, and all the connections. The bar *b*, and the connections which it sustains, are held up by two-arms *b' b'*, which turn on a pivot at their lower ends, and are made in that peculiar shape at their upper ends, near *ff*, to allow the entire manual to be removed in the usual way for repairing, &c., when they, *b' b'*, are placed straight, and the rod *r* is detached from *b* or *t*.

Having described my invention, what I claim therein as new, and desire to secure by Letters Patent, is—

1. I claim the connections *a a*, their nuts, screws, and blocks *d e*, together with their pins, screws, and little ball-supports *e*.
2. I claim the lips *f f* and their guides *g g*.
3. I claim the spring-catch *h* and its attachments *i j k l m n*, and *o*, including the arrangement *p* and *q*.
4. I claim the bar *b* and its supports *b' b'*, as shown and set forth.
5. I claim the combination *s r t u v*, as described and represented.
6. I claim the peculiar hinge-joint made by the sticks *x* and *y* and the plate *z*, with little pins passing through the sticks.
